FLUSHING-VALVE.

1,255,587.

Specification of Letters Patent.

Patented Feb. 5, 1918.

Application filed May 15, 1916. Serial No. 97,541.

To all whom it may concern:

Be it known that I, PERCY F. DE TAMBLE, a citizen of the United States, residing at Chicago, in the county of Cook and State of Illinois, have invented certain new and useful Improvements in Flushing-Valves, of which the following is a specification.

This invention relates to flushing valves for water closets and the like, and has reference more particularly to valves of that type which, when actuated, automatically discharge a predetermined volume of water to the closet bowl, and wherein the volume of water so discharged is capable of regulation according to the amount required for flushing purposes in each individual case.

The general object of the invention is to provide a flushing valve of the type mentioned that shall be characterized by simplicity of structure, certainty and reliability of action, neatness of appearance and economy of space required, and low cost of manufacture. Other and more specific objects are, to provide an automatic flushing valve that shall operate equally well under widely varying water pressures from three pounds upward, to provide an improved valve of that particular type wherein the main water-control valve opens with and closes against the pressure of the inflowing water, to provide improvements in that particular type wherein the main valve closes after discharging a given volume of water whether the operating handle or knob be held open or released, to provide a novel means of adjustment for securing various amounts of water permitting a greater range and finer degree of adjustment than has heretofore been attained, to provide a novel and improved relief valve, to provide a novel and improved structure and location of intake by-pass, and to provide a novel and improved structure and location of outflow by-pass.

Still other objects and advantages secured by the invention will be apparent to those skilled in the art by reference to the following description, taken in connection with the accompanying drawing wherein I have illustrated a practical and preferred embodiment of the invention, and wherein—

Figure 1 is a vertical axial section taken in the plane of the operating handle. Fig. 2 is a similar view of the lower portion of the

structure taken on the line 2—2 of Fig. 1. 55 Fig. 3 is an outer end elevation of the push-rod and its mounting that actuates the relief-valve. Fig. 4 is an inner end view of the push-rod and the eccentric carried thereby. 60

Referring to the drawing, 10 designates a vertical cylindrical casing constituting the main body of the valve structure and formed with a contracted lower end 11 to which the water discharge pipe is attached and, just above its lower end, with a laterally extending boss 12 to which is connected the water supply pipe. 13 designates a cap or cover that has a screw-threaded connection with the upper end of the casing 10, forming a 70 water-tight joint therewith by means of a gasket 14; and 15 designates another laterally extending boss on the side of the casing that surrounds a hole 16 in the wall of the latter for a purpose hereinafter explained. Formed integral with and inside the main casing 10 is a short elbow section 17 that registers with the intake opening formed by the boss 12 and constitutes virtually an upwardly turned extension of the 80 water supply pipe. The upper end of this elbow section forms an annular horizontal valve seat 18, with which co-operates the main water admission and shut-off valve 19. The valve 19, which carries a gasket 20 and a 85 depending baffle 21 that effects the "re-fill" of the closet bowl, is formed on and integral with the lower end of a hollow structure 22 that is in effect a hollow stem for the valve 19 and serves a variety of functions herein- 90 after pointed out, and carries at and integral with its upper end a piston 23 having water-tight sliding engagement with the internal wall of the cylindrical casing 10. Centrally mounted in the piston 23 is an 95 upstanding tube 24, and centrally mounted in the main control valve 19 is a depending tube 25 that slides through a grid or spider 26 in the elbow member 17 and, with the piston 23, serves to guide the vertical move- 100 ments of the valve 19. Rotary movement of the combined structure last described is prevented by means of a guide rib 27 on the internal wall of the casing engaging in a notch 28 in the edge of the valve 19. The 105 tubes 24 and 25 communicate freely at their inner ends with the interior space of the hollow structure 22, and the lower end of

tube 25 is closed except for a fine lateral duct 29 (Fig. 2) just above said closed lower end. The tube 25, hollow structure 22, and tube 24 constitute an intake by-pass for the 5 water, leading into a differential pressure chamber 30 between the piston 23 and the cap 18. In the normal or non-flushing condition of the device the elbow 17, pipe 25, hollow valve stem 22, pipe 24 and chamber 10 10 30 are all flooded with water at the pressure existing in the water main; and the greater area of the piston 23 over that of the lower side of valve 19, plus the weight of the movable structure, keeps the main 15 valve 19 closed. When, however, the pressure in the chamber 30 is relieved, the main valve and the superposed structure rise, and this is accomplished by the following mechanism. In one side wall of the hollow stem 20 22 is formed an inwardly projecting hollow boss 31 that forms a guide and support for the stem 32 of a relief valve 33 that seats against the outer end of the boss 31 and is normally held closed by a spring 34 that 25 abuts against a cap member 35 screwing into an opening 36 in the opposite side wall of the hollow stem 22, said opening 36 permitting the valve 33 and its associated parts to be applied and removed. Attached to the 30 outer end of the valve stem 32 by a ball-and-socket joint 37 is a finger 38 that constitutes in effect a flexible section or extension of the valve stem. This finger 38 extends through a vertical slot 39 in a bracket 40 that is 35 formed as a part of the casting which comprises the parts 19, 22 and 23, and the finger 38 is normally supported in a horizontal position by the lower end of the slot 39.

The tube 24, hollow valve stem 22, and 40 hollow boss 31 together form an outflow by-pass when the relief valve 33 is unseated by the mechanism next to be described.

Within the boss 15 and slidably engaging in the hole 16 is a push-rod 41, on the inner 45 end of which, within the main cylindrical casing 10, is a valve-tripping disk 42 that is eccentric with reference to the axis of the rod, as shown in Fig. 4. This disk 42 lies opposite the outer end of finger 38, as 50 shown in Fig. 1. The rod 41 is packed by a washer 43; and a thin metal disk 44 engaging one face of the washer 43 forms an abutment for a spring 45, the other end of which engages a trip-adjusting head 46 that 55 has a threaded connection with the outer end of rod 41 and slidably fits the bore of the boss 15. The periphery of the head 46 is toothed, as best shown in Fig. 3; and said toothed periphery engages with an inter- 60 nally toothed ring 47 that is countersunk in the outer end of boss 15. The head 46 has a rounded or convex outer face provided with a kerf 48, and this convex face is engaged by the concave inner end 49 of a handle 50. 65 A keeper nut 51 screws onto the outer end

of boss 15 and is formed with an in-turned flange 52 that engages with the inner end 49 of the handle and holds the latter in operative relation to the head of the push-rod.

In the operation of the flushing valve, the inflow conduit 17, tube 25, hollow valve stem 22, tube 24 and differential pressure chamber 30, are filled with water under the pressure of the water main, except for a small 70 body of air in the hollow cap 13. When the handle 50 is tilted in any direction the push-rod 41 and eccentric 42 are forced inwardly and, by contact with the finger 38, open the relief valve 33 which controls the 75 outflow by-pass, thereby permitting the body of water in the differential pressure chamber to vent freely to the lower portion of the cylinder 10 and discharge outlet 11. The water pressure on the lower side of the main 80 valve 19 quickly raises said valve and the superposed parts, permitting the water to overflow the valve seat 18 and rush through the lower portion of the cylinder 10 and discharge outlet 11 to the bowl. During this 85 rising movement of the main valve 19, piston 23, and intermediate parts, the relief valve finger 38 rises over the outer face of the eccentric 42 until its outer end passes the upper edge of the eccentric, whereupon 90 the relief valve 33 instantly closes and re-establishes the water main pressure in the differential pressure chamber 30. As the latter gradually re-fills through the inflow by-pass, the main valve 19 settles to its seat, 95 thus cutting off the main flow of water to the bowl. As the baffle 21 enters the annular valve seat 18, the flow of water is reduced to an annular spray which effects the "refill" of the bowl in a manner well understood. The universal joint 37 between the valve stem 32 and the valve-actuating finger 38 permits the descending movement of the movable structure, and closing of the relief valve 33, even though the push-rod 41 be 100 maintained by the handle 50 in its inward position during such descending movement. The instant the handle 50 is released the spring 45 retracts the push-rod 41 and its eccentric 42, permitting the finger 38 to drop to normal horizontal position. Owing to the large area of the outflow or relief discharge, the upward or valve-opening movement of the parts is practically instantaneous and is ordinarily completed before the 110 actuating handle 50 is released; so that the actual flushing period is determined as to length by the length of the relatively slow descending movement of the main valve and superposed parts. Of course, the greater 115 the upward movement of these parts, the longer will be the period of the descending movement, and the greater the volume of water passed through the flushing valve. This measuring quality of the valve is capa- 120 125 130

ble of nice regulation by shifting the position of the eccentric 42 relatively to the valve actuating finger 38. In the adjustment shown in Figs. 1 and 4 the eccentric

5 42 is set to accommodate a maximum upward travel of the parts. When the push-rod 41 is turned through a half revolution, the low point of the eccentric will be uppermost, and the parts will then be set for the 10 minimum upward movement of the main valve and superposed parts. The eccentric may be set to any intermediate positions between these extremes, depending upon the fineness of the graduation afforded by the 15 coöperating parts 46 and 47, the adjustment being effected by removing the handle 50 and cap nut 51, applying a spanner to the kerf 48, pushing the head 46 inwardly until the teeth thereon pass out of registration 20 with the teeth of the ring 47, then turning the member 46 to the desired extent and then permitting the parts 46 and 47 to again interlock with each other under the action of spring 45.

25 From the foregoing it will be seen that the intake by-pass is constant, and the measuring capacity of the flushing valve is effected by graduating the extent of the rising or opening movement of the main valve 19, 30 this latter in turn being controlled by the time period during which the relief valve 33 is held open.

It will be observed that the construction is of that type wherein the main valve opens 35 with, rather than against, the pressure of the incoming water. This renders the device very sensitive and quick in the opening movement of the main valve, and renders the device particularly efficient in connection 40 with low water pressures; and, since the main valve closes under opposing pressures, it seats gently and noiselessly. The inflow and outflow by-passes are not only wholly within the main cylindrical casing, but also 45 within the single movable member comprising the main valve, piston, and connecting part, thus greatly simplifying the valve in respect both to structure and appearance.

It will be noted by reference to Fig. 2 that 50 the fine duct 29 at the lower end of the intake by-pass tube 25 is located on the rear side of said tube with reference to the direction of flow of the incoming water. The specific location of this duct as shown is 55 important, since it prevents the duct from being clogged or obstructed by sand, grit or any other foreign matter in the water. When the main valve is open and the water is rushing through the elbow conduit 17, it 60 sweeps past, rather than into, the fine duct 29, thus keeping the latter clear of any such obstructions.

From the foregoing it is believed that the 65 manner in which the device of my invention effects the stated purposes thereof will be

readily apparent to those familiar with this art, and, without limiting myself to the precise details shown and described.

I claim:

1. In a flushing valve, the combination 70 with a casing having water inlet and discharge openings, of a main valve controlling the water inlet, a piston connected to said main valve and forming a movable wall of a differential pressure chamber, an intake by-pass between said water inlet opening and 75 said differential pressure chamber, an out-flow by-pass between said differential pressure chamber and said discharge opening, a relief valve in said out-flow by-pass, and 80 manually operable means for opening said relief valve and holding the same open during the opening movement of said main valve, said relief valve being self closing after a predetermined extent of opening 85 movement of said main valve, and said manually operable means being adjustable to hold the relief valve open during varying extents of opening movement of said main valve.

2. In a flushing valve, the combination 90 with a casing having water inlet and discharge openings of a main valve controlling the water inlet, a piston forming a movable wall of a differential pressure chamber, a 95 hollow structure rigidly connecting said main valve and piston and communicating with said differential pressure chamber, an intake by-pass between said inlet opening and said differential pressure chamber, a 100 relief valve in said hollow structure, and manually operable means for opening said relief valve and holding the same open during the opening movement of said main valve, said relief valve being self closing 105 after a predetermined extent of opening movement of said main valve, and said manually operable means being adjustable to hold the relief valve open during varying extents of opening movement of said main 110 valve.

3. In a flushing valve, the combination with a casing, of a movable structure within 115 said casing containing a relief passage, a movable structure and controlling said relief passage, said relief valve having a stem projecting from said movable structure at right angles to the path of movement of the latter, a spring normally tending to close 120 said relief valve, and a push-device mounted in a side wall of said casing and adapted to unseat said relief valve through contact with the outer end of its stem.

4. In a flushing valve, the combination 125 with a casing, of a movable structure within said casing containing a relief passage, a relief valve seat and valve carried by said movable structure and controlling said relief passage, said relief valve having a 130

jointed stem projecting from said movable structure at right angles to the path of movement of the latter, a spring normally tending to close said relief valve, and a 5 push-device mounted in a side wall of said casing and adapted to unseat said relief valve through contact with the outer end of its stem.

5. In a flushing valve, the combination 10 with a casing, of a movable structure within said casing containing a relief passage, a relief valve seat and valve carried by said movable structure and controlling said relief passage, said relief valve having a stem 15 projecting from said movable structure at right angles to the path of movement of the latter, a spring normally tending to close said relief valve, a push rod mounted in a side wall of said casing, a disk eccentrically mounted on the inner end of said push rod and adapted to unseat said relief valve through contact with the outer end of its stem, said push rod being adjustable about 20 its longitudinal axis, and means for locking said push rod in any adjusted position 25 against rotation under its normal endwise movement.

6. In a flushing valve, the combination 30 with a casing, of a movable structure within said casing containing a relief passage, a relief valve seat and valve carried by said movable structure and controlling said relief passage, said relief valve having a jointed stem projecting from said movable structure 35 at right angles to the path of movement of the latter, a spring normally tending to close said relief valve, a push rod mounted in a side wall of said casing, a disk eccentrically mounted on the inner end of said push rod and adapted to unseat said relief valve 40 through contact with the outer end of its stem, said push rod being adjustable about its longitudinal axis, and means for locking said push rod in any adjusted position

against rotation under its normal endwise 45 movement.

7. In a flushing valve, the combination 50 with a casing having a laterally projecting hollow boss, of a movable structure within said casing containing a relief passage, a relief valve seat and valve carried by said movable structure and controlling said relief passage, said relief valve having a stem 55 projecting from said movable structure at right angles to the path of movement of the latter, a spring normally tending to close said relief valve, a push rod mounted in a side wall of said casing and disposed within and coaxial with said hollow boss, a disk eccentrically mounted on the inner end of 60 said push rod and adapted to unseat said relief valve through contact with the outer end of its stem, a peripherally toothed head on the outer end of said push rod, an internally toothed ring in said boss with which 65 said head slidably engages, a spring normally urging said push rod outwardly of said casing, and an operating handle flexibly jointed to the outer end of said boss and engaging the outer face of said head. 70

8. In a flushing valve, the combination of a casing having an inlet and an outlet, a piston-like main valve reciprocable in said casing and controlling communication between said inlet and outlet, an auxiliary 75 valve carried by said main valve and governing the relief of pressure behind the piston-like valve, means by which said auxiliary valve may be temporarily unseated, and a rotatably adjustable plunger with an eccentric on the end engageable with said unseating means to actuate the same and wiped by said unseating means in the opening movement of the main valve, thereby making possible the adjustment of the action of the 80 main valve. 85

PERCY F. DE TAMBLE.
